UNITED STATES PATENT OFFICE.

FREDERICK WILLIAM VICKERY, OF LONDON, ENGLAND.

SHEET-DELIVERY MECHANISM.

1,106,261.

Specification of Letters Patent.

Patented Aug. 4, 1914.

Application filed June 5, 1911. Serial No. 631,457.

To all whom it may concern:

Be it known that I, FREDERICK WILLIAM VICKERY, a subject of the King of Great Britain, residing at London, England, have 5 invented certain new and useful Improvements in Sheet-Delivery Mechanism, of which the following is a specification.

The present invention has reference to sheet delivery mechanisms, and more especially to that type of delivery mechanism which includes sets of feeding bands, pressing and bending devices for acting on the sheets co-operatively with each other and with said bands, and gages for insuring the 15 proper stacking of the sheets after the latter have passed the aforementioned appliances or instrumentalities.

It comprehends certain improvements in or relating to the mounting of the feeding 20 appliances, whereby the same may be moved or removed bodily as a whole on and from the machine without interfering with the other parts thereof; further improvements in the construction and arrangement of the 25 said appliances; and still further improvements in or relating to the delivery table and its mounting, all of which improvements are hereinafter described at length.

An embodiment of the invention is illustrated in the accompanying drawings, wherein—

Figure 1 is a side elevation, partly in section, of the improved delivery mechanism; Figs. 2 and 3 are, respectively, a side elevation, likewise with parts in section, and a plan view, of a modified arrangement of the structure shown in Fig. 1; Figs. 4 to 7, inclusive, are detail views of various modification in the construction and arrangement of 40 the appliances and parts thereof included in or associated with the delivery mechanism and the delivery table; Figs. 8 and 9 are detail views of the means for raising the delivery table; and Figs. 10 and 11 are detail 45 views of a further modification.

As shown in said drawings, the improved delivery mechanism consists primarily of one or more sets of bands 1, presser rollers 3, benders 27 and gages 22 connected with a 50 single element, which is preferably in the form of a longitudinally-disposed rod 19 and is itself so supported in the machine that it may be moved bodily thereon or removed bodily therefrom and, with it, the set or sets 55 of appliances above referred to.

When only one sheet of paper is being delivered at a time, in the machine, two of the mechanisms shown in Fig. 1 are employed, with one gage 22 at each side of the sheet; but when two or more sheets are being delivered side by side at one time, the mechanism shown in Figs. 2 and 3 is utilized, with one gage between each pair of adjacent sheets, as will be understood. These gages are always at the sides of the sheets and 60 never at the center thereof.

Referring more particularly to Fig. 1, each rod 19 carries a socket piece 18 held thereon in adjusted position by a set screw 20, which socket piece is pivotally connected 70 to a bracket 15 provided with jaws 16 that straddle a transversely-arranged rod 12, one of said jaws being fastened to said rod 12 by a set screw 17. The rod 12 just mentioned is secured to a pair of brackets 13 75 which, in turn, are carried by a pair of posts 14 positioned upon opposite sides of the machine. In this construction, each set of appliances is carried by a single supporting rod 19, the number of such sets being dependent on the number of sheets of paper to be acted upon. These appliances are preferably connected to their rods in the following manner: To the forward portion of the rod there is affixed a pair of spaced brackets 80 21 provided with pins 24 upon which a gage 22 is suspended, the latter being formed with vertical slots 23, through which the pins project, so as to permit it to move up and down and thus accommodate itself to the height 90 or angle of the receiving table. (not shown), the sheets being fed onto said table from delivery table 2, to which latter they are fed from the cutting mechanism, (not shown), by a belt 38 passing at one end around a 95 roller 9, as is customary. The rear bracket 21 has an extension 25 to which is pivoted at 26 one of the wedge-shaped benders 27, the extension and bender being provided with stops 28 to limit the downward movement of said bender and insure the proper 100 positioning of its point when the mechanism is ready for use. Adjacent its rear end, rod 19 carries a tubular bracket 28^a provided with jaws 29 that straddle a second transverse rod 30 employed to steady rod 19. To this bracket 28^a is pivotally connected at 31 the arm 4 that carries the presser roller 3, said arm having a forked upper end 32 which engages a stop 33 on said bracket, 110

whereby the downward movement of the arm is limited, as will be understood. Roller 3 is located at the lower end of arm 4, and to its supporting shaft is rigidly secured a pulley 35 connected by one of the bands 1 with a second pulley 7 which is mounted upon the free upper end of an arm 34, the latter being pivoted at its lower end to the aforesaid supporting shaft. To control the movement of arm 34, that arm is provided with an extension 36 carrying a set screw 37 which rests at its lower end upon arm 4. Motion is imparted to roller 3 and pulley 35 (and, from said pulley, by band 1 to pulley 7), by means of a driving roller 10, with which the former roller contacts, the driving roller receiving its own motion in any suitable manner, as, for instance, by a belt 388 connecting its supporting shaft with that of the pulley 9.

The general operation is substantially as follows: The paper in sheet form is fed along belt 38 onto the inclined portions of the benders 27, (two of which are positioned at the required distance apart), where it is passed up the inclines and comes in contact with the bands 1, these bands being preferably inclined at about the angle shown, so that the paper is curled upward. This bending or curling of the paper corrects or neutralizes its normal tendency to curve or curl downward, so that the sheets issuing between the rollers 3 and 10 pass between the gages 22 onto the receiving table 35 and, on striking the same, straighten out and lie perfectly flat.

It will be seen from the foregoing that when the set screw 17 has been withdrawn the supporting rod 19 may be moved on or removed bodily from the machine, carrying with it the entire set of above-mentioned appliances comprising the delivery mechanism, without interfering with the other parts and instrumentalities comprehended in the machine. This operation, moreover, may be facilitated by attaching a suitable handle 39 to the bracket 15.

In the construction shown in Figs. 2 and 3, two sets of arms 4 and 34 are controlled by a single rod 19 and are adjustable as to distance apart to suit the position of the sheets of paper under operation, the presser rollers 3 being arranged to act on separate sheets, between which sheets one bender 27 and a gage 22 are positioned. To effect this control, the rear end of rod 19 is formed with a bearing 40 and a perforated boss 41. In bearing 40, and upon opposite sides thereof, are journaled intermediate their ends a pair of arms 19^a and 19^b having divergent rear portions which at their free ends are connected to eyes 42 provided upon the rear ends of the adjacent arms 4. The forward portions of the arms 19^a and 19^b are provided with slotted quadrants 43 and

44 which may be moved relative to boss 41 to properly position the arms 4 and their appurtenances, the whole being locked by a belt passed through said quadrants, and through the perforation in said boss. With this construction, the entire delivery mechanism may be moved bodily on the machine, or the benders and gages may be removed bodily from the machine, in which instance the bracket 15 is disengaged from rod 12 and the ends of arms 19^a and 19^b removed from eyes 42, as will be understood.

When it is desirable that the presser roller 3 run out of square or line with the driving roller 10, (and this deviation need only be very slight), the arms 4 may be permanently set, *i. e.*, initially constructed and arranged at the proper angle to effect the required positioning of said presser rollers, as shown in Fig. 4, or the same result may be obtained by providing a suitable pivotal mounting for arms 4. The object of this is as follows: When the sheets reach the delivery mechanism, they sometimes have a fullness, and they are also caused to bulge toward the center at times on passing over the benders; in either instance, a crease is produced in the sheet, and when that part of the sheet reaches the presser rollers, the crease is deepened or made permanent and the sheet is marked or broken, but by setting the presser rollers slightly out of square or line with the driving roller the former tend to pull out the sheet straight and flat, without causing the tires carried thereby to appreciably wear, mark or injure the thinnest paper.

The arms 34 carrying the pulleys 7 may also carry a series of small wheels 45 extending throughout practically their entire length, as shown in Fig. 5, which wheels are normally positioned in close proximity to table 2 but are capable of rising with said arms when the table is raised. The wheels referred to may be driven by the bands 1, or in any other suitable manner.

The table 2 may be replaced by a series of wheels or rollers 46, (see Fig. 6), driven in unison by a band 47^a, or may be provided with a series of these wheels or rollers which are set therein, and in either instance the arm 34 may be formed as a smoother, as indicated by the numeral 47 in Fig. 6, this smoother extending from the presser roller 3 back over the feed belt 38.

The presser rollers may be provided with tires 48, as shown in Fig. 7, and since these rollers are of slightly larger diameter than the pulleys 35 no appreciable wear takes place upon the bands which connect said pulleys with the pulleys 7, as said bands are thus maintained out of frictional engagement with the driving roller 10.

In practice a considerable amount of damaged paper is fed to the delivery mech-

anism, especially when a new set of reels is being started, when the reels break, and at the ends of the reels; these damaged sheets stack unevenly and frequently choke up the 5 delivery mechanism if not full-sized, in which case they must be pulled out by hand, with the result that the bands are often displaced from the pulleys and the cutting mechanism is stopped. To obviate this defect, means is provided for raising the table 10 2, such means preferably consisting, as shown in Figs. 1 and 2, and in detail in Figs. 8 and 9, of a hand lever 52 connected to said table by a link 51. When the lever 15 52 is turned from its normal position shown in Fig. 8, into the position shown in Fig. 9, the connecting link 51 and consequently, the table are drawn upwardly, the sheets are free to drop thereunder into the pit, the 20 elevated end of the table lifts the pulley 7 slightly, and the latter, through a stop 65 on arm 34, raises arm 4 and thus carries roller 35 out of frictional engagement with the driving roller 10.

25 In certain types of machine, and when working on certain classes of paper, it is found desirable to make the rollers 3 as light and narrow as possible. In this case, the bands 1 are replaced by endless belts 48', 30 (Figs. 10 and 11), constructed with a gripping surface of rubber or leather; these belts are preferably of V, D, or analogous section, and fit in correspondingly-shaped peripheral grooves in the pulleys 7 and 35, to prevent 35 their displacement.

The operation and advantages of the entire invention are believed to be apparent from the foregoing, and further description thereof is accordingly omitted.

40 I claim as my invention:

1. In a sheet delivery mechanism for machines of the class specified, the combination, with a main supporting element and a carrier to which said element is removably 45 connected; of a presser roller, a bender and a gage connected to said element and movable bodily with the same on the machine and removable bodily with said element from the machine.

50 2. In a sheet delivery mechanism for machines of the class specified, the combination, with a main supporting element and a carrier to which said element is movably and removably connected; of a pair of brackets 55 and an arm connected to said element and bodily movable and removable with the same on and from the machine, a gage carried by said brackets, a bender pivoted to one of said brackets, and a presser roller carried 60 by said arm.

3. In a sheet delivery mechanism for machines of the class specified, the combination, with a longitudinally-disposed rod, and a carrier in which said rod is movably and 65 removably mounted; of a presser roller, a

bender, and a gage connected to said rod and movable and removable bodily with the same on and from the machine.

4. In a sheet delivery mechanism for machines of the class specified, the combination, with a longitudinally-disposed rod, and a carrier in which said rod is movably and removably mounted; of a pair of brackets and an arm connected to said rod and movable and removable bodily with the same 70 on and from the machine, a gage carried by said brackets, a bender pivoted to one of said brackets, and a presser roller carried by said arm.

5. In a sheet delivery mechanism for machines of the class specified, the combination, with a main supporting element, a carrier therefor, and a table disposed beneath said element; of a driving roller disposed adjacent one end of said table, an 80 arm pivoted at one end to said element and extending across said table, said arm being provided at its free end with a presser roller normally in frictional engagement with said driving roller, a pulley fast on the supporting shaft of the driven roller, an arm pivoted to said shaft and extending across said table in the opposite direction from the first-named arm, a pulley carried by the second-named arm at its free end, and a band 85 connecting said pulleys.

6. In a sheet delivery mechanism for machines of the class specified, the combination, with a main supporting element, a carrier therefor, and a table disposed beneath said element; of a driving roller disposed adjacent one end of said table, an arm pivoted at one end to said element and extending across said table, said arm being provided at its free end with a presser roller normally 90 in frictional engagement with said driving roller, a pulley fast on the supporting shaft of the driven roller, an arm pivoted to said shaft, and extending across said table in the opposite direction from the first-named arm, a pulley carried by the second-named arm at its free end, a band connecting said 95 pulleys, and means carried by said second-named arm for engagement with said first-named arm to determine the normal position 100 of the former.

7. In a sheet delivery mechanism for machines of the class specified, the combination, with a main supporting element, a carrier therefor, and a table disposed beneath said element; of an arm pivoted at one end to said element and extending across said table, said arm being provided at its free end with a presser roller, a pulley fast on the supporting shaft of said roller, an arm 110 pivoted to said shaft and extending across said table in the opposite direction from the first-named arm, a pulley carried by the second-named arm at its free end, a band 115 connecting said pulleys, and means for rais- 120

ing and lowering said table relative to said arms.

8. In a sheet delivery mechanism for machines of the class specified, the combination, with a main supporting element, a carrier therefor, and a table disposed beneath said element; of an arm pivoted at one end to said element and extending across said table, said arm being provided at its free end with a presser roller, a pulley fast on the supporting shaft of said roller, an arm pivoted to said shaft and extending across said table in the opposite direction from the first-named arm, a pulley carried by the second-named arm at its free end, a band connecting said pulleys, a link pivoted to one end of said table, and a lever connected to said link for raising and lowering said table.

9. In a sheet delivery mechanism for machines of the class specified, the combination, with a main supporting element, a carrier therefor, and a table disposed beneath said element; of a bracket carried by said element and provided with a stop, an arm pivoted at one end to said bracket and having means at that end arranged to normally engage said stop, for supporting said arm in one position, a revolute member carried by said arm at its free end, a pulley fast on the supporting shaft of said member, an arm pivoted to said shaft and extending across said table in the opposite direction from the

first-named arm, a pulley carried by the second-named arm at its free end, a band connecting said pulleys and means carried by said second-named arm for engagement with said first-named arm to determine the normal position of the former.

10. In a machine of the class specified, the combination, with a transversely-arranged element and a support therefor, of a bracket provided with a forked end straddling said element and removably attached thereto and with a socket, a longitudinally-arranged element mounted in said socket and supported thereby, and sheet delivery and bending means and a gage carried by the second-named element.

11. In a sheet delivery mechanism for machines of the class specified, the combination, with a main supporting element, and a carrier to which said element is removably connected; of sheet delivering and bending means and a gage connected to said element and movable and removable bodily with the same on and from the machine.

In testimony whereof I have hereunto set my hand in presence of two subscribing witnesses.

FREDERICK WILLIAM VICKERY.
